MATTHIAS UHRMACHER, OF DUISBURG-RUHRORT, GERMANY, ASSIGNOR TO THE FIRM:
VEREINIGTE STAHLWERKE AKTIENGESELLSCHAFT, OF DUSSELDORF, GERMANY

FROG FOR GROOVED RAILS

Application filed April 3, 1928, Serial No. 267,044, and in Germany November 4, 1927.

As with frogs for railway crossings and points with grooved rails the load acting upon the rail is changed from the rims of the running wheels to their flanges, the grooves of said frogs are highly strained and thus exposed to considerable wear.

Various attempts have been made to reduce said wear as much as possible and thereby to increase the life of the frogs.

10 For instance, the whole frogs are made of refined steel, for example of cast manganese steel. Such frogs have, however, the drawback that due to bad possibility of fitting them with the adjoining rails bumping holes are easily produced at these places. Such bumping holes may also be produced at the point of intersection of the frog since the latter can receive at this place a certain wall thickness only and the formation of 20 flaws in the structure of the material cannot be avoided with certainty.

It has also been proposed to insert in the track groove of the frog double-cheek V pieces, which however do not always tightly 25 fit therein and are therefore liable of soon becoming loose by action of the load thereon, while furthermore they tend to drive the lateral bounding webs of the groove outwards. Finally, by the insertion of such 30 double-cheek V pieces in frogs formed of normal grooved rails a very unfavourable stress is exerted upon the groove projecting laterally beyond the web of the rail, said detrimental action being not neutralized even 35 with the employment of filling fish-plates screwed to the web of the rail below the groove.

The present invention provides an improved frog or insertion for railway crossings and points with grooved rails, in which the drawbacks above-mentioned are avoided, said frog being wearproof and thus of long life.

The invention consists in the combination 45 of the following methods namely in the use of rolled thick-web rails, in the insertion of wearproof filling pieces with alternating bridging over of the butt-joints in same as also in the particular shape of the filling 50 pieces and welding only on one side. A fur-

ther remarkable feature consists in that the thick-web rails are of symmetric cross-section so that the filling piece rests at all points over the thick-web of the rail and is thereby supported by the rail. Finally the invention consists also in that the thick-web rails are adapted at the ends to the standard rail section thereby enabling the frog to be welded to the joining rails.

The individual methods are hereinafter 60 more fully described.

The frog is formed of thick-web rails, of which the head has a groove of which the cross-sectional dimensions are larger than those of the normal groove, the grooves in the heads of said thick-web rails being, after the frog has been formed thereof, filled-in by wear-proof filling-pieces, for instance of manganese steel, in such a way that the interrupted rail receives a filling piece bridging over the continuous rail, while the interrupted filling-piece is inserted in the head of the continuous thick-web rail, for the purpose of making all working surfaces of the frog wearproof with a minimum use of refined steel and at the same time making the frog bumpproof.

By the interrupted rails being bridged over by the continuous wearproof filling pieces, which according to the invention can 80 also be formed as V pieces, while in the continuous rail interrupted filling pieces are inserted, butt-joints are produced in the race of the filling-pieces only. Said butt-joints, due to the firm support of the filling piece 85 ends by the web of the thick-web rail, cannot produce bumping holes.

This invention relates further to the particular formation and arrangement of the filling pieces in the thick-web rails. According to the invention, the head grooves and the filling pieces may have the cross-section of a parallelogram. Suitably, the arrangement is then such that the thick-web rail has a plain groove bottom on which bear the filling pieces with their horizontal undersides, so that thereby a uniform and reliable transmission of pressure is ensured. Suitably, the cross-section of the groove and of the filling piece is so oblique-angled that the fill- 95 100

ing pieces undercut the running head of the rail. Due to said undercutting on the running side, a welded seam only is required, for reliably fastening the filling pieces on the other side, namely the guide-rail side, whereby changes of structure are perfectly avoided on the running head side.

The thick-web rail, which according to the invention may be symmetric, offers then a guarantee for a good support of the endangered places, since the filling-pieces are supported directly by the web of the rail.

The ends of the thick-web rails can be tapered to suit the section of the adjoining rails so that a good welding between both may take place, especially if the same material is used for the adjoining rails and for the thick-web rails of the frogs whereby undesired transition shocks are avoided. At the transit places from the adjoining rail to the thick-web rail, fish-plate seats may be cut in the latter corresponding to the thickness of the webs of the normal rails so that for joining the rails normal fish plates can be used. At the crossings where the thick-web rails abut each other, the latter can be connected by their projecting web ends or by suitably bent fish-plates, so that there no fish-plate seats need to be cut out. The symmetric formation of the thick-web rails offers, for instance, the advantage that, for example, frog outer fish-plates, which are to grip with one end below the head side of one rail and with the other end below the groove side of the other rail, need not be bent and can besides be profiled for longitudinal-seam welding.

A particular advantage of the improved frog or insertion consists in the fact that for straight crossings the same cross-section of the rolled filling pieces can be used at the inner rail as well as at the outer rail. For curved crossings, at the inner rail and at the outer rail, either the same cross-sections of the filling pieces can be used, in which subsequently the plain groove and the ramp are cut, or, different cross-sections may be used with the plain groove rolled therein.

The improved frog formed of thick-web rails has thus the following advantages, (1) over similar frogs formed of normal rails: long life because the race in the rail groove, that is highly loaded by the wheel flange, consists of manganese steel; no open butt joints in the frog; no bending of outer fish-plates; (2) over cast manganese steel frogs: good possibility of fishing and no formation of bumping holes at the butt-joints; possibility of aluminothermic welding of the butt-ends of the rails; no formation of bumping holes at the point of insertion of the frog due to good support by the thick-web, whereas with manganese steel frogs said place can receive a small wall thickness only and the formation of flaws in the material cannot be avoided with certainty.

The manufacture and the working of the improved frog is rather economic, because its life due to the employment of refined steel (manganese steel) at all the endangered places thereof is equal to that of frogs wholly cast of manganese steel. As the rather expensive refined steel is used at those places only where it is actually required, that is, mainly at the places where the frog comes in contact with the wheel flange, but not at the other parts, for instance at the feet, webs, and so on, the total costs of manufacture are considerably lower than those of cast manganese steel frogs, which especially for frog knee-pieces and curved crossings are rather high due to the requirement of special moulds for casting the latter.

In spite of lower costs of manufacture of, and of the advantages attained by, the improved frog, the latter has an equal life to that of cast manganese steel frogs, which is very important from the economical point of view.

The accompanying drawings illustrate diagrammatically by way of example a preferred constructional form of the improved frog and its details forming the subject matter of the present invention:

Fig. 1 is an end view of a symmetric thick-web rail used for forming the improved frog of such rails;

Fig. 2 is a plan view of a frog for switches;

Fig. 3 is a cross-section on the line 3—3 of Fig. 2;

Fig. 4 is a cross-section on the line 4—4 of Fig. 2;

Fig. 5 is a cross-section on the line 5—5 of Fig. 2;

Fig. 6 is a cross-section on the line 6—6 of Fig. 2;

Fig. 7 is a cross-section on the line 7—7 of Fig. 2;

Fig. 8 is a cross-section on the line 8—8 of Fig. 2;

Fig. 9 is a cross-section on a larger scale through the head of the interrupted rail shown in Fig. 2;

Fig. 10 is a plan view of a railway crossing comprising the improved frogs as a curved crossing;

Fig. 11 is a cross-section on the line 11—11 of Fig. 10;

Fig. 12 is a cross-section on the line 12—12 of Fig. 10;

Fig. 13 is a cross-section on a larger scale through the head of the right-hand thick-web rail shown in Fig. 11;

Fig. 14 is a cross-section on a larger scale through the head of the outer curved rail shown in Fig. 10, i. e. the right hand rail of Fig. 12; and

Fig. 15 is a cross-section through the head of a thick-web rail showing the filling-piece therein formed as a V piece.

Referring to Fig. 1:—The thick-web rail

5 S used for forming the improved frog of such rails, is of symmetric cross-section, Z designating the outer fish-plates for joining the thick-web rails and which need not be bent and are profiled for a longitudinal-seam welding.

10 Referring to Fig. 2:—a designates the continuous thick-web rail, in which the interrupted filling pieces b^1 and b^2 of wearproof steel are inserted, while c^1 and c^2 designate the interrupted thick-web rail bridged over by the continuous filling piece d .

15 Referring to Fig. 3 there is shown the groove bed of the continuous wearproof filling piece d which bridges over the continuous rail a with the interrupted rails c^1 and c^2 rising from both ends towards the centre of the filling piece for the purpose of thereby forming a mounting surface for the wheel flange.

20 Figs. 4 to 8 show the arrangement of the filling piece in suitable cross-section through the different points, so as to render more clear the position and shape of the filling piece. For example the cross-sections clearly show that the continuous filling piece d is inserted in the interrupted rails c^1 and c^2 whereas the interrupted filling pieces b^1 are arranged in the continuous rail a^1 and that further the groove bed, as can be seen from Fig. 3, rises towards the middle.

25 Referring to Fig. 9, which shows the head of the thick-web rail c^1 with the inserted filling piece d on a larger scale:—On the guide rail side of the thick-web rail c^1 the filling piece d is inclined and connected with the latter by means of a longitudinal seam welding e , while on the running head side of the thick-web rail is undercut at f . The parallelogram formation and arrangement in the 30 rail head, of the filling piece, are obvious from the illustration.

35 Referring to Figs. 10 to 14:— g designates the thick-web rails, and h the filling pieces inserted therein and which always undercut the rail at the running head side and are welded thereto at the guide rail side. The illustrations show clearly that the grooves of the rail heads and also the running grooves in the 40 filling pieces inserted in the rail head grooves, are suitably arranged in accordance with the stresses of wear to be expected by the load of the wheel flange acting upon the same.

45 As shown in Fig. 15, the filling-piece d can be formed as a V piece simply by inclining its side walls i , k toward one another in downward direction (see dotted lines), the insertion of said filling-pieces in the rail head being thereby considerably facilitated.

50 What I claim is:—

55 1. A wear-resisting crossing, comprising in combination a thick web grooved continuous rail, thick web grooved intersecting rails, a wear-resisting continuous insert of manganese steel in the tread of each intersecting

60 rail bridging said continuous rail, and a wear-resisting interrupted insert in said continuous rail bearing with its joint faces against the inserts of said intersecting rails.

65 2. A wear-resisting crossing as specified in claim 1, comprising wear-resisting inserts of parallelogram-shaped cross section with side faces inclined so that said inserts engage under the rail tread.

70 3. A wear-resisting crossing as specified in claim 1, comprising wear-resisting inserts of wedge-shaped so that the imaginary downwardly directed extension of the inclined side faces of the inserts intersect each other.

75 4. A wear-resisting crossing as specified in claim 1, comprising thick web rails of symmetric shape.

80 In testimony whereof I have hereunto set my hand.

MATTHIAS UHRMACHER.
